UNITED STATES PATENT OFFICE.

CHARLES L. WEIHE, OF NEW MINDEN, ILLINOIS.

FAUCET.

SPECIFICATION forming part of Letters Patent No. 671,153, dated April 2, 1901.

Application filed December 28, 1900. Serial No. 41,395. (No model.)

To all whom it may concern:

Be it known that I, CHARLES L. WEIHE, a citizen of the United States, residing at New Minden, in the county of Washington and State of Illinois, have invented certain new and useful Improvements in Faucets, of which the following is a full, clear, and exact description, reference being had to the accompanying drawings, forming a part hereof.

10 My invention has relation to improvements in faucets; and it consists in the novel construction of faucet more fully set forth in the specification and pointed out in the claims.

In the drawings, Figure 1 is a middle vertical longitudinal section taken through the casing and stuffing-box, the remaining parts being in elevation. Fig. 2 is an inverted plan view of the outer end of the faucet. Fig. 3 is a front end view, and Fig. 4 is a side elevation, of the device.

The present invention is specially applicable for drawing off liquids which are in their nature slow running, like molasses, heavy oils, glycerin, and the like, though I do not 25 wish to limit its application to that class, as the faucet may be used for drawing off liquids of any character whatever. In the case of viscid fluids, however, the present device assists their natural flow in effecting their escape from the cask or vessel confining them.

In detail the invention may be described as follows:

Referring to the drawings, 1 represents the outer casing or tube, having a front enlargement 1', behind which is the delivery-nozzle 2. The latter is surrounded by a ring of cork 3, projecting a suitable distance beyond the nozzle, the said cork ring being held in place by an annular metallic band 4. The edge of 40 the cork ring 3 coöperates with the pivoted gate or cut-off 5, provided at its free end with a knob 6 and pivotally mounted in a pocket 7, within which it is free to turn in one direction only, (as a precautionary measure.) 45 Within the casing 1 is mounted a twist-box 8 on the order of an auger, the forward stem 9 of which operates in a stuffing-box 10, a suitable packing-ring 11 being placed about the stem to the rear of the follower of the stuffing-box. Over the outer square or polygonal end 50 of the stem 9 is passed a crank-arm 12, by

which the twist-bar 8 is rotated. The inner end of the casing 1 is preferably screw-threaded for attaching the casing to a cask or barrel 13, containing the liquid to be drawn. 55

The contact between the cork 3 and the gate 5 makes a tight joint, preventing the liquid from dripping when the gate is closed. By locating the nozzle 2 to the rear of the enlargement 1' it is practically concealed from 60 view, and there is little danger of children or unauthorized persons opening the gate 5 and allowing the contents of the cask to go to waste.

Additional safety is imparted to the device 65 by allowing the gate 5 to swing in but one direction, the pocket 7 opening laterally from the base of the enlargement 1'. With very thick or viscid fluid the operator after opening the gate or valve 5 (swinging it in the direction shown by the dotted position in Fig. 2) imparts rotation to the twist-bar 8 by turning the crank-arm 12 in proper direction, the twist or auger having the effect of delivering 70 the fluid along the spiral passage of the said auger and forcing it positively through the delivery-nozzle 2.

It is apparent, of course, that minor changes may be made in the device without departing from the spirit of my invention. 80

Having described my invention, what I claim is—

1. A faucet having an outer casing, a delivery-nozzle located a suitable distance from the forward end thereof, a gate carried by the 85 casing adjacent to the nozzle and adapted to close the mouth of the same, a twist-bar in said casing, a stem forming a part of said bar and projecting from the forward end of the casing a suitable distance, a stuffing-box for 90 said stem, and means interposed between the gate and the nozzle for effecting a tight joint between them, substantially as set forth.

2. A faucet having an outer casing, a forward enlargement forming a part thereof, a delivery-nozzle to the rear of said enlargement, a gate pivoted at the base of the enlargement and adapted to close the mouth of the nozzle, a twist-bar in said casing, a stem forming a part of said bar and projecting forward from the casing a suitable distance, a stuffing-box for said stem, and means carried 100

by the nozzle for effecting a tight joint with the gate, substantially as set forth.

3. A faucet comprising a casing, a delivery-nozzle leading from the same, a pivoted gate, a cork ring carried by the periphery of the nozzle and projecting a suitable distance beyond the same and coöperating with the gate, a band for retaining said cork ring on said nozzle, and means for positively forcing the

liquid through the casing to the nozzle, substantially as set forth.

In testimony whereof I affix my signature in presence of two witnesses.

CHARLES L. WEIHE.
